UNITED STATES PATENT OFFICE

94,908

DESIGN FOR A BUILDING

Bert Knaster, Maplewood, and Charles F. Vonhof,
Hillside, N. J.

Application January 12, 1935, Serial No. 54,834

Term of patent 14 years

To all whom it may concern:

Be it known that we, Bert Knaster and Charles F. Vonhof, citizens of the United States, residing, respectively, in Maplewood, county of Essex, State of New Jersey, and in Hillside, county of Union, State of New Jersey, have invented a new, original, and ornamental Design for a Building, of which the following is a specification, reference being had to the accompanying drawing, forming a part thereof.

Fig. 1 is a front elevation in perspective of the device showing our new design;

Fig. 2 is a top plan view.

We claim:

The ornamental design for a building, as shown.

In testimony whereof, we have signed this specification.

BERT KNASTER.
CHARLES F. VONHOF.
